COMBINED STRAINER AND FAT SEPARATOR FUNNEL

Elizabeth S. Jablecki, 1422 Damon Court SE.,
Rochester, Minn. 55901

Filed Apr. 29, 1975, Ser. No. 572,744

Term of patent 14 years

Int. Cl. D7—99

U.S. Cl. D7—68

FIG. 1

FIG. 2

FIG. 3

FIG. 5

FIG. 1 is a side elevational view of a combined strainer and fat separator funnel showing my new design.

FIG. 2 is a rear elevational view thereof.

FIG. 3 is a top plan view thereof.

FIG. 4 is a front elevational view thereof.

FIG. 5 is a bottom plan view thereof.

I claim:

The ornamental design for a combined strainer and fat separator funnel, as shown.
